UNITED STATES PATENT OFFICE.

CHARLES L. BALDAUF, OF WEST HOBOKEN, NEW JERSEY, ASSIGNOR TO THOMAS NELSON & SONS, OF NEW YORK, N. Y., A CORPORATION OF NEW YORK.

LOOSE-LEAF BINDER.

1,071,500.

Specification of Letters Patent.

Patented Aug. 26, 1913.

Application filed September 14, 1907. Serial No. 392,928.

To all whom it may concern:

Be it known that I, CHARLES LOUIS BALDAUF, a citizen of the United States, residing in the town of West Hoboken, county of 5 Hudson, State of New Jersey, have invented new and useful Improvements in Loose-Leaf Binders, of which the following is a specification.

My invention relates to a device for binding loose leaves between two boards in such a manner that any one or more of the leaves may be readily removed, and others inserted. While this invention may be applied to 10 loose-leaf ledgers, or scrap books, or to other 15 similar articles, I have designed it particularly for use in connection with a loose-leaf dictionary, or encyclopedia, which is to be supplied from time to time with additional insertion pages of printed matter and from 20 which pages may have to be removed from time to time.

In the drawings, Figure I shows in perspective the preferred form of my new binder; Fig. II is a sectional view of the 25 same form of binder with pages inserted, the section being made through one of the binding posts shown in Fig. I; Fig. III shows a binder of another form, partially open to permit the insertion or removal of pages; 30 and Fig. IV illustrates the locking device of the binders shown in Figs. I and III.

In Fig. I *a* is the front cover or side, and *b* the rear cover of my improved binder. These covers are preferably made integral 35 with the back portion *c*. Bars *d*, *e*, preferably made of metal, are attached to the rear and front covers *a*, *b* respectively (Figs. I and II) by any suitable means. The stiffening of the covers is preferably interrupted just in front of the bars in order that the forward portion of each cover may be readily opened and closed without affecting the position of the bars. The bar *e* is provided with a plurality of pins or bars *f*, extending parallel to the back portion *c*. These bars are provided at their free ends with apertures *g* adapted to receive pins or projections *h* carried by the bar *d*.

As shown in Fig. II a number of sheets 50 of paper, such as the printed pages of a book, provided with perforations corresponding in position to that of the pins or bars *f*, may be slipped over said pins or bars *f*, and the pins or projections *h* may be

slipped into the apertures *g* so as to lock the 55 sheets of paper into place. In order to prevent the pins or projections *h* from slipping out of the apertures *g* when the book is handled, I provide a locking device. This locking device consists of a bar *e'* preferably integral with the bar *e*, and extending at right angles from one end thereof, and bar *d'* preferably integral with the bar *d* and extending at right angles from one end thereof, the bars *d'* and *e'* extending in opposite directions, but lying in parallel planes. 60 By means of a binding screw *e''*, inserted in bar *e'*, and extending through slot *d''* in bar *d'* I am enabled to lock the bars *d'* and *e'*, and through them, the bars *d* and *e*, and the 65 pins *f*, *h*, for the purpose described. Such a locking device is preferably provided at both the bottom and the top of the book. The head of the binding screw is preferably provided with a slot of sufficient size to enable 70 the screw to be turned with the aid of a coin. The bars with their locking extensions constitute a frame comprising two oppositely disposed substantially U-shaped members, their backs being secured to the 75 inner surfaces of the covers and the arms of one member slidably engaging with the arms of the other member.

In Fig. I I have shown the slot *d''* closed at each end. When the binding screw is 80 loosened, the back portion *c* falls away from the pins *f*, into the position shown in Fig. IV. When the book is to be relocked the back portion *c* is pushed forward until the pins *h* are in registry with the apertures *g*, 85 the pins are pushed down into the apertures, and the bars *d'* *e'*, which have reassumed the position shown in Fig. I, are relocked by a turn of the binding screw. Instead of the pins *f*, *h*, I may employ channeled bars *f'* 90 and corresponding flat bars *h'*, as shown in Fig. III. Moreover instead of the back *c* shown, a telescopic back may be employed, one portion being integral with the front cover *a* and the other composed of two parts, 100 each united to or integral with the back cover *b*. When the telescoping back is employed the slot of the locking device is made open at its lower end in order to permit the front cover *a* to be lifted away, and entirely 105 removed from, the book proper. The locking device is adjustable, as will readily be understood, the range of adjustability being

determined by the length of the slot and the width of the back of the book.

I claim:

In a loose leaf binder, a frame comprising
5 two oppositely disposed, substantially U-shaped members, a leaf holding pin mounted on the base of one of said members, means on the base of the other of said members for engaging the end of said pin, and means for 10 slidably and pivotally connecting the arms of said U-shaped members together and for securing the members in adjusted position,

whereby said members may be moved away from each other for releasing the pin engaging means and then swung on their pivotal 15 connections to permit the removal and introduction of sheets or leaves.

In testimony whereof I have hereunto set my hand this 12th day of September, 1907.

CHARLES L. BALDAUF.
